UNITED STATES PATENT OFFICE

101,239

DESIGN FOR AN AUTOMOBILE HEATER CASING

John R. Morgan, Oak Park, Ill., assignor to Sears,
Roebuck and Co., Chicago, Ill., a corporation
of New York

Application July 20, 1936, Serial No. 63,947

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for an Automobile Heater Casing, of which
the following is a specification, reference being
had to the accompanying drawing, forming a
part thereof.

The drawing is a perspective view of an auto-
mobile heater casing embodying my new design.

The side and bottom of the device (not shown)
are similar in appearance to the side and top
shown in the drawing.

I claim:

The ornamental design for an automobile
heater casing, as shown and described.

JOHN R. MORGAN.
